DEVICE ON HARNESSES FOR PARACHUTES
FITTED WITH QUICK RELEASE DEVICE

Carl Herman Lundholm, Stockholm, Sweden

Application August 7, 1947, Serial No. 767,084
In Sweden May 10, 1940Section 1, Public Law 690, August 8, 1946
Patent expires May 10, 1960

18 Claims. (Cl. 244—151)

1

The present invention relates to a device for parachute harnesses fitted with a so called quick release device. Its chief object is to provide means so that two straps passing between the legs of the wearer and fastened in the quick release device are effectively carried to the sides, and, at the same time, the said straps are freed quickly, after they have been released from the quick release device. Still another object is to produce a simple and convenient harness to wear during and after the jump.

The invention refers principally to that category of harnesses which are provided with a U-shaped strap, which is preferably a continuation of the suspension straps leading to the parachute, and is adapted to pass under the seat of the wearer. At the lower portion of the strap, called the seat strap, there are arranged two other straps, "leg straps," which in use, pass between the legs of the wearer upwards at the front, then, through loop shaped members arranged at the lower part of the harness by which they are carried slidably to the sides and finally releasably fastened in the quick release device. When the latter is opened, the leg straps are first disengaged from the same, and are then intended to slide through the loop shaped members mentioned, whereby the wearer gets free from the leg straps and the rest of the harness.

The principal object of the invention is to effect a new and useful improvement of the said loop shaped members.

It is already known to make the said loop shaped members of short straps of the same material as used in the rest of the harness, both ends of such straps being connected to the uprising portions of the U-shaped strap. In order to reduce the friction between those straps and the leg straps, when the latter slide through, the former are bordered with some smooth material such as leather. This device, however, has certain drawbacks. Thus there may arise a tightening of the leg straps around the thighs of the parachutist during the jump, which is very inconvenient. Further the side carrying straps may clinch the leg straps during their passage, and finally the former, when exposed to moisture, may present a substantial friction to the latter.

In an old type of parachute harness, two substantially rectangular rings of metal have been proposed through which rings leg-encircling straps are slidably passed and then releasably connected in the quick release device. Apart from the fact that there is no U-shaped strap passing under the seat of the wearer to which the

leg straps may be connected, the shape of the said rings is such that they are hardly suitable for letting through fastening members on the free strap ends such as snap hooks. The absence of a U-shaped strap under the seat makes this harness very uncomfortable during a jump, the whole weight of the body of the jumper being taken up by the leg-encircling leg straps.

According to the present invention all the said drawbacks have been removed.

In addition to means for facilitating and expediting the passage of the leg straps through the loop shaped members, means are proposed, by which the maximum load of the parachutist during a jump is taken up by the U-shaped strap thereby eliminating any inconvenient tightening of the leg straps around his legs.

Still another object of this invention is to provide means for increasing the comfort of the upper portion of the harness during the jump by removing the suspension straps leading to the parachute, from the head of the jumper.

With respect to the loop shaped members for carrying the leg straps effectively to the sides, two new forms of construction are proposed, both being rigid members fixed to the U-strap by special straps. The said rigid members are characterized in that the inner portions of the same, adjacent the portion against which the leg straps in use are adapted to slide, are bent obtusely from the said portion thereby producing a wide loop with no risk of sticking even if snap hooks are used as fastening members for the harness locking device.

The first form consists of a staff shaped member preferably of metal with a substantially straight middle portion but whose ends are arranged at rather obtuse angles to that portion viz. preferably not less than about 140 degrees. In these ends, slots are provided for the fixing of one short strap in each end. The middle portion is preferably about 6 cm. long. The ends are in use directed towards the longitudinal middle of the harness in front of the wearer. Through this arrangement a rather wide loop is obtained which permits the fastening members of any sort, thus also snap hooks, to pass through unhindered. All edges being rounded, the passage is also very smooth.

In order to prevent the leg straps from falling down upon any of the fastening straps, the free portion of the lower fastening straps has a length of 10 to 12 cm. and is fixed to the U-shaped strap at a distance of 20 to 25 cm. from its centre under the seat of the wearer. The free portion

of the upper fastening strap has preferably a length of 8 to 10 cm. and is placed at a distance of about 15 cm. from the lower one. With such an arrangement, the middle portion of the metal member, on a properly adjusted harness, gets situated at the upper end of the groin of the wearer. Further the lower fastening straps form substantially right angles in relation to the uprising portions of the U-straps, by reason of which the leg straps slide through easily, even if they should be slack, which is usually the case, when the aviator takes off the harness when standing still on the ground.

In order to remove the risk of the staff shaped member tilting over towards the centre of the harness when exposed to a strain, the ends of the same are made much broader, than the middle portion, or about 22 mm. as against 10 mm. for the latter. The longitudinal sides of the ends, which in use are turned to the sides, are preferably 12 mm., the slot 5 mm. and the other longitudinal sides 5 mm. It is also advantageous to provide the portion of the staff ends adjoining the middle portion with nose shaped projections of a length of about 15 mm. and a base of about 10 mm. These projections serve both the purpose of preventing tilting over and increasing the smooth sliding surface for the leg straps. A number of sewing holes on the said projections serve to secure the same to the fastening straps. The upper edges of the two lower fastening straps should be bordered with leather to afford protection, when the leg straps slide through in a slack condition.

In case the free strap ends connected with the quick release device are fitted with snap hooks which may present the risk of getting stuck anywhere, the middle portion of the staff shaped member is made fairly thick or about 10 mm. as against about 4 mm. for the ends of the same. Further all edges of the said member are rounded off. To facilitate a smooth passage of the leg straps, the adjustment buckles should be placed as low as possible, so that they do not have to pass the staff shaped member on release. Finally, the shoulders, which arise at the point of fixture of the strap ends through the webbing, being folded doubly, should be removed, by arranging a short rectangular piece of leather or some other suitable material of tapering thickness at the said point.

In order to increase the convenience of the harness for the aviator during a jump, an additional strap of about 20 cm. is preferably arranged at the middle of the lower fastening strap and, with its other end, at a rather sharp angle to the seat strap. Such a strap has proved to be a good support for the outside of the thigh of the wearer during a jump.

The second form of construction consists of a rounded ring arranged at each side of the lower portion of the harness by means of two short straps. The said ring may be substantially circular or oval. If circular, the diameter should be at least 80 mm., if oval, the breadth minimum 80 mm. and the height 60 mm. or about $\frac{1}{2}$ of the height. In an oval ring, it is advantageous that the portion which in use is directed towards the middle of the harness be somewhat broader than the opposite end. Slots for fixing the fastening straps are provided at the lateral short end and the lower longitudinal side, the former strap being about 10 cm. long and arranged 40 cm. from the centre of the U-strap under the seat at an angle of about 60 degrees, the latter strap being

about 20 cm. from the said centre at an angle of about 120 degrees.

In addition to fixing the ring the lower fastening strap serves as a support for the thigh of the jumper thereby increasing the comfort during a jump.

The invention is illustrated by way of example in the accompanying drawings:

Fig. 1 shows a parachute harness with staff shaped members.

Fig. 2 shows a staff shaped member with fastening straps and part of a leg strap.

Fig. 3 is a plan view of the staff shaped member.

Fig. 4 shows a lateral view of a staff shaped member.

Fig. 5 shows a rhomboid buckle for the suspension straps.

Fig. 6 is a harness with a substantially oval ring attached by two straps.

Fig. 7 is a perspective view of an oval ring.

1 are the upper portions of the suspension straps leading to the parachute. 1¹ is the lower U-shaped portion of the suspension straps of the leg strap. 1² are the upper portions of the suspension straps which are releasably fastened in the quick release device. 3 are two straps which cross each other on the back of the wearer. 4 shows a waist strap. 5 are the upper and 6 are the lower fastening straps for the rigid member.

7 is a support strap of support for the outside of the thigh, the upper end being fixed to strap 6 and the lower end to the leg straps 1¹. 8 is the quick release device. 9 shows the staff shaped member, 10 are rhomboid shaped buckles for connecting and adjusting the suspension strap, 11, 12 are buckles for the adjustment of the leg straps and the waist strap. 13 is a strap on the back, shortly below the neck of the wearer, and serves to join the suspension straps. 14 is a handle for the manual release of the parachute, 15 is a releasing cable leading from the handle to the parachute. 16 is a broad strap for attaching of the handle 14. 17 are fastening members at the free strap ends. 18 is the middle portion, 19 the upper end and 19¹ the lower end of the staff shaped member 18. 20 are slots in the same for the fixing of the fastening straps 5 and 6. 21 is the longitudinal side of the end 19 directed inwards, and 22 the long side directed outwards of the ends 19, 19¹. 23 is a nose shaped projection on the staff shaped member 18. 24 are sewing holes for securing of the fastening strap 6. 25 are the upper broad slots and 26 the lower narrow slots of the rhomboid shaped buckles 10. 27 shows a substantially oval ring, the main portion being designated 27¹ and the slots for fixing the fastening straps 27².

Several variations within the scope of the invention are possible without departing from the principle thereof.

Having now described the invention and the manner in which the same is performed, what I claim is:

1. Device on a harness for parachutes fitted with a quick release device and a U-shaped strap adapted to be passed under the seat of the wearer, to which two leg straps are fixed, which latter straps, in use, pass between the legs of the wearer upwards at the front, then carried slidably to the sides through loop-shaped members arranged at the lower part of the harness, and finally releasably fastened in the quick release device, said loop-shaped members consisting of a rigid member preferably of metal in which the inner portions adjoining the portion against which the

leg straps are adapted to slide in use are bent obtusely from the said portion and which member is connected to the U-shaped strap preferably by means of special fastening straps.

2. A device as claimed in claim 1, wherein the rigid member is fixed to the U-shaped strap by at least two fastening straps.

3. A device according to claim 1, in which the rigid member consists of a substantially straight middle portion and two opposite end portions, said end portions being adapted for the attachment of the fastening straps and forming obtuse angles in relation to the middle portion and being in use directed to the longitudinal middle line of the harness in front of the wearer.

4. A device according to claim 1 in which the rigid member consists of a substantially straight middle portion and two opposite end portions, said end portions being adapted for the attachment of the fastening straps and forming obtuse angles in relation to the middle portion and being in use directed to the longitudinal middle line of the harness in front of the wearer, the said end portions being arranged at angles of not less than 140 degrees relatively to the middle portion.

5. A device according to claim 1 having a rigid member with a substantially straight middle portion and two opposite end portions, said end portions being adapted for the attachment of the fastening straps and forming obtuse angles in relation to the middle portion and being, in use, directed to the longitudinal middle line of the harness in front of the wearer, the middle portion of the said rigid member, in a properly adjusted harness, being situated about the upper end of the groin of the wearer.

6. A device according to claim 1 having a rigid member with a substantially straight middle portion and two opposite end portions, said end portions being provided with longitudinal slots for the attachment of the fastening straps and forming obtuse angles in relation to the middle portion, said ends being in use directed to the longitudinal middle line of the harness in front of the wearer, and at least twice as broad as the middle portion, the longitudinal portions of said ends which in use are directed outwards to the sides of the harness being about twice as broad as the longitudinal portions, which are directed inwards to the longitudinal middle line thereof in front of the wearer.

7. A device according to claim 1 having a rigid member with a substantially straight middle portion and two opposite end portions, said end portions being provided with longitudinal slots for the attachment of the fastening straps and forming obtuse angles in relation to the middle portion, said ends being, in use, directed inwards to the longitudinal middle line of the harness in front of the wearer, the said end portions being further provided with nose-shaped projections which are arranged at those sides thereof, which in use, are directed outwards to the sides of the harness, said projections serving to prevent the rigid member from tilting over when the harness is subjected to the load of the wearer and also to increase the smooth sliding surface for the leg straps.

8. A device according to claim 1 having a rigid member which consists of a substantially straight middle portion and two opposite end portions, said end portions being adapted for the attachment of the fastening straps and forming obtuse angles in relation to the middle portion and being in use directed to the longitudinal middle line

of the harness, the rigid member being secured to the uprising portions of the U-shaped seat strap by means of two fastening straps, the one being arranged above the other, the lower fastening straps forming substantially right angles in relation to the uprising portions of the U-shaped strap.

9. A device according to claim 1 having a rigid member which consists of a substantially straight middle portion and two opposite end portions, said end portions being adapted for the attachment of the fastening straps and forming obtuse angles in relation to the middle portion and being in use directed inwards to the longitudinal middle line of the harness in front of the wearer, the rigid member being connected to the uprising portions of the U-shaped seat strap by means of two fastening straps, the one being arranged above the other, an additional strap being arranged with the upper end secured to the lower fastening strap and the lower end at a relatively acute angle to the seat strap.

10. A device on a harness for parachutes fitted with a quick release device and a U-shaped strap adapted to be passed under the seat of the wearer to which two leg straps are connected which, in use, pass between the legs of the wearer upwards at the front of the wearer, then carried slidably to the sides through loop-shaped members arranged at the lower part of the harness, and finally releasably fastened in the quick release device, said loop-shaped members consisting of rigid rings preferably of metal which rings are connected to the U-shaped strap by means of at least two fastening straps.

11. A device as claimed in claim 10, wherein the rigid rings are connected to the U-shaped strap each by one upper and one lower fastening strap, the upper strap being connected to the uprising portion of the U-shaped strap and at the outer end of the ring, whereas the lower strap is connected to the lower seat portion of the U-shaped strap and to the lower edge of the ring.

12. A device according to claim 10, in which one of the fastening straps is connected to the lateral end and the other to the lower side of the ring, the lower fastening strap being substantially twice as long as the upper fastening strap.

13. A device as claimed in claim 10, wherein the rigid rings are connected to the U-shaped strap by one upper and one lower fastening strap, the upper strap being connected to the uprising portion of the U-shaped strap and at the outer end of the ring, whereas the lower strap is connected to the lower seat portion of the U-shaped strap and to the lower edge of the ring, the distance from the centre of the U-shaped seat strap to the point of attachment of the upper fastening strap being substantially four times the free length of said fastening strap.

14. A device according to claim 10, in which the rigid ring is connected by one upper and one lower fastening strap the upper strap being connected to the uprising portion of the U-shaped strap at an angle of about 60 degrees and the lower strap at an angle of about 120 degrees relatively to the underlying portions of the U-strap.

15. A device according to claim 10 in which the rigid ring is of substantially circular shape.

16. A device according to claim 10, in which the rigid ring is of substantially oval shape.

17. A device according to claim 10 in which the rigid ring is of substantially oval shape, the height thereof being about two thirds of the width.

18. A device according to claim 10, in which the rigid ring is of substantially oval shape, the end of said ring which in use is directed inwards towards the longitudinal middle line of the harness being somewhat wider than the opposite end.
